(57) **CLAIM**

The ornamental design for a display cart as shown and described.

DESCRIPTION

FIG. 1 is a top front perspective view of a display cart;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a bottom rear perspective view thereof;
FIG. 9 is a top front perspective view thereof, shown in an environment of use; and,
FIG. 10 is a right side elevation view thereof, shown in an environment of use.

The uniform broken lines shown in FIGS. 1-8 illustrate portions of the display cart that form no part of the claimed design. The broken lines illustrating the monitor in FIGS. 9 and 10 are environment, while the remaining broken lines in FIGS. 9 and 10 illustrate portions of the display cart that form no part of the claimed design.

1 Claim, 9 Drawing Sheets
